DESIGN FOR A COMBINED SEAT BACK AND WASHBASINS UNIT

Otto Kuhler, Blauvelt, N. Y., assignor to American Car and Foundry Company, New York, N. Y., a corporation of New Jersey

Application November 6, 1945, Serial No. 123,515

Term of patent 14 years

(Cl. D4—2)

To all whom it may concern:

Be it known that I, Otto Kuhler, a citizen of the United States, residing in Blauvelt, in the county of Rockland, State of New York, have invented a new, original, and ornamental Design for a Combined Seat Back and Washbasin Unit, of which the following is a specification, reference being had to the accompanying drawings, which form a part thereof, in which

Fig. 1 represents an elevational view of the seat back showing my new design of the combined seat back and washbasins unit;

Fig. 2 is an end view of the unit when in an upright position.

Fig. 3 is a plan view showing the washbasin side of the combined seat back and washbasins unit, and

Fig. 4 is an end view showing the unit in folded position permitting use of the washbasins.

The dotted line disclosures of the seat portions in Figs. 2 and 4 are for illustrative purposes only.

I claim:

The ornamental design for a combined seat back and washbasins unit, as shown and described.

OTTO KUHLER.
